(57) CLAIM

The ornamental design for a hosiery garment, as shown and described.

DESCRIPTION

FIG. 1 is a perspective view of a hosiery garment in accordance with the present invention;

FIG. 2 is a front elevational view thereof;

FIG. 3 is a rear elevational view thereof;

FIG. 4 is left side elevational view thereof;

FIG. 5 is a right side elevational view thereof;

FIG. 6 is a top plan view thereof; and,

FIG. 7 is a bottom plan view thereof.

The dotted lines shown throughout the drawings illustrate claimed stitching in the hosiery garment.
